Attorneys.

UNITED STATES PATENT OFFICE.

OLE O. STORLE, OF TACOMA, WASHINGTON.

SPARKING DEVICE FOR INTERNAL-COMBUSTION ENGINES.

1,291,234.

Specification of Letters Patent. Patented Jan. 14, 1919.

Application filed December 22, 1916. Serial No. 138,520.

To all whom it may concern:

Be it known that I, OLE O. STORLE, a citizen of the United States, residing at Tacoma, in the county of Pierce and State of Washington, have invented certain new and useful Improvements in Sparking Devices for Internal-Combustion Engines, of which the following is a specification, reference being had to the accompanying drawing, forming 10 a part thereof.

This invention relates to sparking apparatus of the "make and break" type.

The main objects of the invention are to insure the production of an effective spark 15 at the proper point in the stroke of the piston for the ignition of the charge; to provide for self-cleaning of the contacts; to insure a gas tight joint between the contact piece or member attached to the cylinder and the circuit connection therewith, by the elimination 20 of a movable or loose bearing; to provide for the repetition of the spark on each firing stroke of the piston, to insure ignition or for varying the time of the spark with relation 25 to the stroke of the piston; and generally to improve the construction and operation of devices of this class.

The accompanying drawing shows a "make and break" sparking device embodying the invention as applied to the cylinder and piston of an internal combustion engine, a portion of the cylinder being shown in axial section.

The device comprises a spring contact arm 35 or member *a*, which may be conveniently made of cast iron, and is formed or provided at one end with a laterally projecting nose and at the other end with a screwthreaded shank *b*, which is fitted and secured by a nut 40 *c* in an aperture of a recessed cap *d*, threaded or otherwise removably attached to the head of the cylinder *e*. The shank of the contact arm is suitably insulated from the cap *d*, and forms a gas-tight joint therewith, which 45 is not liable to become loose or leaky, as the shank does not revolve or otherwise move in said cap, but is normally fixed therein so that it is not subjected to wear.

The other contact piece or member of the 50 sparking device, consisting of one or more disks *f* and *g*, two being shown in the present case, is formed or provided with a stem *h*, which is threaded and adjustable axially in a lug or boss *i* on the piston *j*, and is secured 55 in adjusted position by a lock nut *k*, or it

may be adjustably mounted on and secured to the piston in any other suitable manner.

The laterally projecting free end or nose of the spring contact arm *a*, or the periphery of each of the contact disks *f* and *g*, are 60 either or both beveled or rounded, so that the disk or disks in passing the nose or end of the spring contact arm, will insure an effective contact and keep the contact faces clean. 65

To avoid wear of the contact disk or disks unevenly and to bring different parts of their peripheries into service, the stem *h* may be turned more or less and set in a new position in the boss *i*, or the same result may be 70 attained by angular adjustment of the shank *b* in the cap *d*.

The insulated shank of the spring contact arm *a* is connected, as shown diagrammatically in the drawing, with one terminal of an 75 electric circuit, including a battery *l* or other source of electricity, and timing mechanism *m*, of the usual or any suitable construction, the other terminal of the circuit being connected with the cylinder or frame of the 80 engine.

In the operation of the device, when either of the disks *f* or *g* passes the nose or free end of the spring contact arm *a* on the firing stroke of the piston, the circuit being closed 85 by the timing mechanism at the time of engagement of said disk with the contact arm, a strong spark or series of sparks is produced at the instant contact between the disk and arm is broken. 90

The timing mechanism may be so made and adjusted that a spark will be produced by the engagement and disengagement of either or both disks with the contact arm.

By the employment of a number of contact disks in connection with the usual timing mechanism, the spark may be advanced and retarded more or less, for starting and for normal running. 95

When two or more disks are used and the 100 timing mechanism is constructed and adjusted for varying the time of the spark, the disk *g* nearest the piston, is set or adjusted to produce a spark on or near the dead center of the crank at the beginning of the 105 firing stroke of the piston for starting, and the other disk *f* is set or adjusted to produce an earlier spark, according to the adjustment of the timing mechanism, for normal running. 110

Various modifications in details of construction and arrangement of parts may be made without departure from the principle and scope of the invention as defined in the 5 following claim.

I claim:

In a sparking device for internal combustion engines the combination with timing mechanism for controlling an electric circuit 10 and varying the time of the spark, of a con-

tact member comprising a plurality of spaced disks attached to and movable with the piston, and a laterally yielding spring contact arm attached to the cylinder in the path of said disks, which coöperate therewith to produce a spark according to the adjustment of the timing mechanism. 15

In witness whereof I hereunto affix my signature.

OLE O. STORLE.
